UNITED STATES PATENT OFFICE.

ABRAHAM BRAHADI, OF MONTREAL, QUEBEC, CANADA.

HAT OR CAP.

SPECIFICATION forming part of Letters Patent No. 376,705, dated January 17, 1888.

Application filed August 10, 1887. Serial No. 246,639. (No model.)

To all whom it may concern:

Be it known that I, ABRAHAM BRAHADI, of the city of Montreal, in the district of Montreal and Province of Quebec, Canada, have 5 invented certain new and useful Improvements in Head-Gear; and I do hereby declare that the following is a full, clear, and exact description of the same.

My invention has reference specially to fur 10 caps provided with ear laps or muffs; and it consists in a new construction of such ear-laps and a novel arrangement of them with reference to the cap.

I propose to form in the substance of the 15 cap, preferably between the outside and the lining and just above the ears, pockets or recesses of sufficient size to allow the ear-laps to slide up into them and be completely hidden therein. The ear-lap itself, of any usual and 20 desired shape and material, is formed upon an outside frame of wire or other material, which will give a certain amount of stiffness and at the same time be somewhat of a springy nature. To the upper edge of the ear-lap is attached a strip of heavy silk, satin, or like material, (usually of width equal to that of the 25 ear-lap,) the opposite edge of which is secured to the lining of the recess at a point about half-way up it. This strip or band, while preventing the ear-lap from becoming detached 30 from the cap, does not serve to hold it in place either when down or when pushed up into the

recess, this being effected by the pressure of the head of the wearer against the slightly resilient frame of the ear-lap. 35

For full comprehension of my invention reference must be had to the annexed drawings, forming part of this specification, in which—

Figure 1 is a view taken through the substance of the cap and showing the recess and 40 ear-lap down; Fig. 2, a similar view showing the ear-lap in the recess, and Fig. 3 the frame of ear-lap.

Similar letters of reference indicate like parts. 45

A shows the cap, in the thickness of which is formed the recess shown, B. C is the ear-lap, made on an outside frame, C'; and D, the strip of silk or like material secured to the upper edge of C and to the side of the recess 50 along the line b.

Having thus described my invention, I beg to state that what I claim is as follows:

The combination, with a hat or cap having side pockets or recesses, of a flexible strip, as 55 D, within such recess, and an ear-tab having a metallic stiffening-frame secured to said strip and capable of sliding in said recess, substantially as set forth.

A. BRAHADI.
